ELECTRIC CAN OPENER

Douglas W. Anderson, Palatine, Ill., assignor to Burgess Vibrocrafter, Inc., Grayslake, Ill., a corporation of Delaware

Application October 24, 1957, Serial No. 48,236

Term of patent 14 years

(Cl. D22—2)

Fig. 1

Fig. 2.

Fig. 1 is a perspective view, showing the front, left side and top of an electric can opener embodying my new design, and

Fig. 2 is a perspective view showing the top, right side and rear thereof.

The essential features of the design reside in the portions shown in solid lines on the drawing.

I claim:

The ornamental design for an electric can opener, substantially as shown and described.
